UNITED STATES PATENT OFFICE.

WILLIAM S. MCLEWEE, OF TRENTON, NEW JERSEY.

DESIGN FOR A LAMP-SHADE.

SPECIFICATION forming part of Design No. 21,581, dated May 24, 1892.

Application filed April 30, 1892. Serial No. 431,357. Term of patent 7 years.

To all whom it may concern:

Be it known that I, WILLIAM S. MCLEWEE, a citizen of the United States, and a resident of Trenton, Mercer county, and State of New Jersey, have invented a new and original Design for Lamp-Shades, of which the following is a specification, reference being had to the accompanying drawing, forming a part thereof.

10 Referring to the drawing, the figure represents a side view of a lamp-shade formed according to my design.

The leading feature of my design consists in the ornamental flange or collar surrounding the opening in the top of the shade.

15 *a* represents the body of the shade, and *b* the ornamental flange or collar surrounding the opening in the top of the same. Said flange or collar extends upward from the body *a* in an outwardly tapering or flaring line to a point *b'* and extends inwardly from the latter point in a short tapering line to a

point *b* and terminates in a short vertical line *b'*. A series of narrow raised stems *c*, having a series of elongated beads *c'*, connecting at one end with the upper end of the same, are formed on the lower portion of the collar or flange *b* at short distances apart, and between the stems *c* are formed a series of raised portions *d*, which taper from their base 20 at the base-line of the flange or collar to a point at their upper end. A rounded bead or collar *e* surrounds the flange or collar *c* at its point of union with the body *a* of the shade.

Having thus set forth my invention, what 25 I claim, and desire to secure by Letters Patent of the United States, is—

The design for a lamp-shade, as herein shown and described.

WILLIAM S. MCLEWEE.
